BUILDING PANEL

Harold A. Edmondson, 257 S. Arden Blvd.,
Los Angeles, Calif.

Filed Mar. 13, 1961, Ser. No. 64,234

Term of patent 14 years

(Cl. D13—1)

FIG 1

FIG 2

FIG 4

FIG 3

FIG. 1 is a front view of building panel showing my new design;

FIG. 2 is a side edge view;

FIG. 3 is a fragmentary back view of the building panel with the bottom portion thereof omitted for convenience in illustration only; and

FIG. 4 is a top edge view of FIG. 3 thereof.

I claim:

The ornamental design for a building panel, substantially as shown and described.
